US0D1057673S

(12) **United States Design Patent** (10) Patent No.: **US D1,057,673 S**
(45) Date of Patent: ** Jan. 14, 2025

(54) **BUTTON**

(71) Applicant: **London Luxury**, New Rochelle, NY (US)

(72) Inventor: **Steven Schwartz**, New Rochelle, NY (US)

(73) Assignee: **LONDON LUXURY, LLC**, New Rochelle, NY (US)

(**) Term: **15 Years**

(21) Appl. No.: **29/817,079**

(22) Filed: **Nov. 29, 2021**

(51) LOC (15) Cl. **13-03**

(52) U.S. Cl.

USPC **D13/174**

(58) **Field of Classification Search**

USPC D13/133, 171, 173, 174, 177, 199;

(57) **CLAIM**

The ornamental design for a button as shown and described.

DESCRIPTION

FIG. 1 is a top perspective view of a button showing a new design;

FIG. 2 is a top view thereof;

FIG. 3 is a front view thereof, the back view being a mirror image;

FIG. 4 is a right side view thereof, the left side view being a mirror image; and,

FIG. 5 is a top perspective view of the button of FIG. 1 shown in an operating environment attached to a portion of a substrate.

The broken lines in the drawings illustrate portions of the button and environmental subject matter that form no part of the claimed design.

1 Claim, 3 Drawing Sheets
